UNITED STATES PATENT OFFICE

WALTER G. NAGLE, OF BELLEVILLE, AND MAX LEHMAN, OF QUINCY, ILLINOIS, ASSIGNORS TO BAKER NAGLE COMPANY, OF BELLEVILLE, ILLINOIS, A CORPORATION OF DELAWARE

DESIGN FOR A HEATER

Application filed January 8, 1930. Serial No. 34,057. Term of patent 3½ years.

To all whom it may concern:

Be it known that we, WALTER G. NAGLE and MAX LEHMAN, citizens of the United States, residing at Belleville, St. Clair County, Illinois, and Quincy, Adams County, Illinois, respectively, have invented a new, original, and ornamental Design for Heaters, reference being had to the accompanying drawing, forming part thereof.

We claim:

The ornamental design for a heater, as shown.

WALTER G. NAGLE.
MAX LEHMAN.
